CLAIM

(52) U.S. Cl.

The ornamental design for a display screen or portion
thereof with graphical user interface as shown and
described.

USPC D14/486; D14/490

DESCRIPTION

(58) Field of Classification Search

The file of this patent contains at least one drawing/photograph
executed in color. Copies of this patent with color
drawing(s)/photograph(s) will be provided by the Office
upon request and payment of the necessary fee.

The sole FIGURE is a front view of a display screen or
portion thereof with graphical user interface showing the
claimed design.

The peripheral dashed broken lines depict a display screen
or portion thereof, and form no part of the claimed design.
The interior broken lines depict portions of the graphical
user interface which form no part of the claimed design.
